UNITED STATES PATENT OFFICE

ERNEST HUFF, OF MILWAUKEE, WISCONSIN, ASSIGNOR TO AMERICAN LACE PAPER COMPANY, OF MILWAUKEE, WISCONSIN, A CORPORATION OF WISCONSIN

DRINKING CUP DISPENSER

Application filed March 5, 1931. Serial No. 520,201.

This invention relates to improvements in drinking cup dispensers.

It is the object of the invention to provide a novel and simple form of dispenser having no moving parts and in which a stack of paper cups or like articles is supported on fixed flanges so designed as to provide adequate support for the stack, to permit the withdrawal of individual cups from the bottom of the stack, and to minimize the resistance to such withdrawal.

There have been numerous attempts to devise dispensers for paper cups and the like in which fixed flanges would take the place of movable escapement mechanisms. It has, however, been characteristic of the fixed flange devices that they have either been inaccurate in permitting the escape of more than one cup at a time or else have afforded so much resistance as to be very difficult of operation. The present invention seeks to overcome these objections by a design in which the dispensing flanges are spaced apart for a distance less than the distance between the marginal bead portions of the cups to be dispensed and are so arranged with reference to the enclosing barrel as to provide space into which the distorted marginal bead portion of the cup may expand during its successive clearance of the flange members which oppose its discharge. Since clearance is provided for but one cup bead at a time, the device functions accurately in discharging individual cups and since the cup bead clears the projecting flanges successively instead of simultaneously, the resistance to withdrawal is minimized. Hence a device embodying the present invention functions smoothly to permit the withdrawal of single cups from a stack easily and without undue resistance or distortion.

In the drawing:

Figure 1 is a vertical axial section from front to rear through a device embodying this invention.

Figure 2 is a fragmentary detail view in a vertical axial section at right angles to the plane in which Figure 1 is taken.

Figure 3 is a bottom plan view of the device shown in Figure 1.

Like parts are identified by the reference characters throughout the several views.

The dispensing device comprises a sleeve 5 provided at its rear with a boss 6 having a dovetailed slot at 7 to engage a mounting plate 8. The intermediate portion of the slot 7 is deep enough to secure the heads of screws used to support the mounting plate. The mounting plate has lateral notches, one of which is shown at 9, and which are adapted to receive set screws 10 inserted from the sides of boss 6, as shown in dotted lines in Figure 3.

The sleeve 5 is counter bored to receive tube 11 which is supported on shoulder 12 with its interior surface flush with the adjacent interior wall of tube 5. Tube 11 may comprise the usual tubing of glass or other material for retaining the upper portion of the stack of cups to be dispensed.

Below tube 11 the interior surface of dispensing sleeve 5 tapers very slightly inwardly, as shown at 15, toward a shoulder 16 at which the transverse dimension of the interior bore through sleeve 5 is substantially enlarged in a lateral direction. The diameter of the sleeve portion 15 immediately above shoulder 16 is made to correspond closely to the diameter of the beads of the cups to be dispensed, thus receiving the stack and permitting it free axial movement while substantially eliminating possibility of lateral movement of the lowermost cups.

At the front and rear of the interior wall surfaces of the sleeve 5 just below shoulder 16 are flanges 17 and 18 which project centrally to materially restrict the internal diameter of sleeve 5 from front to rear. These flanges have beveled upper surfaces and are very slightly offset in a vertical direction so that they will not simultaneously oppose their maximum resistance to a given cup which is being dispensed therefrom. The offset is preferably less than the distance between corresponding bead portions of consecutive cups in the stack. Below the flanges 17 and 18 the internal periphery of sleeve 5 again becomes cylindrical as shown at 20, its diameter being the same as the transverse di-

mension immediately below shoulders 16 at the sides of the device.

When a stack of cups is in the dispenser, the marginal bead portions of the lowermost cup will rest simultaneously on both of the flanges 17 and 18, the offset of flange 17 above flange 18 being insufficient to cause flange 17 to take the entire load. When the operator grasps the lower portion of the 10 lowermost cup to effect withdrawal thereof from the dispenser the resistance offered to the front and rear portions of the bead of the cup by flanges 17 and 18 causes distortion of the bead portion of the cup whereby 15 its transverse diameter is increased as compared with its diameter from front to rear. The increase in transverse diameter is accommodated by the enlarged bore 20 below shoulders 16. The shoulders 16 are so located with reference to the height of flanges 17 and 18 as to be adapted to receive only the bead portion of the lowermost cup, thereby preventing more than one cup from being dispensed. In this connection it should 25 be noted that the offset of shoulder 18 below shoulder 17 is not essential to the operation of the device but does contribute materially to the smoothness of the operation since, as above noted, the maximum resistance 30 of the shoulders 17 and 18 is consecutive instead of being concurrent.

When one side of the cup passes flange 17 it immediately springs out to its normal circular form, thus relieving the cup distortion at one side. The other side of the cup is undergoing an increasing distortion at the moment due to flange 18 but immediately afterward this part of the cup also is relieved and the cup passes freely from the dispenser.

40 I have found that the freedom of dispensing action can be controlled quite largely by the extent of flanges 17 and 18. If such flanges are of less extent than they are illustrated in Figure 3, the dispenser tends to 45 function inaccurately. If the extent of the flanges is increased they afford an unnecessarily great resistance to the dispensing operation. Preferably they should be slightly less than 90° in extent as shown.

50 While I have referred to cup distortion herein, I wish to make it clear that such distortion as occurs is preferably very slight, the dispenser size being accurately worked 55 out with reference to accurately sized cups to be dispensed.

I claim:

1. A dispensing device comprising a sleeve having a stack receiving portion, a cup delivering portion of greater diameter than said stack receiving portion, circumferentially spaced means between said portions adapted to engage the marginal bead portion of the lowermost cup of a stack, said 60 sleeve being recessed intermediate said cup

engaging means to receive bead portions of a single cup passing said means.

2. A dispensing device comprising a sleeve having a portion adapted to receive a stack of cups having beaded margins and a plurality of circumferentially spaced means within said sleeve for engaging the margin of the lowermost cup of said stack, said means being axially spaced not to exceed the distance between corresponding marginal portions of two successive cups in the stack, and diametrically spaced sufficiently less than the diameter of the beads of the cups to slightly distort a cup as it passes 75 said means.

3. A dispensing device comprising a sleeve having a portion adapted to receive a stack of nested cups with beaded margins, the diameter of said portion being at least as great as the diameter of the cups received therein, circumferentially spaced flanges projecting inwardly from the inner periphery of said sleeve for the releasable support of the bead portion of the lowermost cup of such a stack, the wall of said sleeve intermediate said flanges being recessed to receive portions of said cup slightly distorted by withdrawal between said flanges.

4. A dispensing device comprising a sleeve having a portion adapted to receive a stack of nested cups with beaded margins, the diameter of said portion being at least as great as the diameter of the cups received therein, circumferentially spaced flanges projecting inwardly from the inner periphery of said sleeve for the releasable support of the bead portion of the lowermost cup of such a stack, the wall of said sleeve intermediate said flanges being recessed to receive portions of said cup slightly distorted by withdrawal between said flanges, the axial extent of said recess above said flanges being insufficient to receive bead portions of more than one cup.

5. A dispensing device comprising a sleeve having a portion adapted to receive a stack of nested cups with beaded margins, the diameter of said portion being at least as great as the diameter of the cups received therein, circumferentially spaced flanges projecting inwardly from the inner periphery of said sleeve for the releasable support of the bead portion of the lowermost cup of such a stack, the wall of said sleeve intermediate said flanges being recessed to receive portions of said cup slightly distorted by withdrawal between said flanges, the axial extent of said recess above said flanges being insufficient to receive bead portions of more than one cup, the recessed wall being carried out to the end 110 of said sleeve.

6. A dispensing device comprising a sleeve having a portion adapted to receive a stack of nested cups with beaded margins, the diameter of said portion being at least as 125

great as the diameter of the cups received therein, circumferentially spaced flanges projecting inwardly from the inner periphery of said sleeve for the releasable support of
5 the bead portion of the lowermost cup of such a stack, the wall of said sleeve intermediate said flanges being recessed to receive portions of said cup slightly distorted by withdrawal between said flanges, the axial
10 extent of said recess above said flanges being insufficient to receive bead portions of more than one cup, said flanges being slightly offset axially whereby to oppose successively their maximum resistance to the passage of a
15 cup while acting simultaneously thereon.

7. In a cup dispensing device the combination with means providing a channel for cups to be dispensed, of means restricting said channel at circumferentially spaced points,
20 said channel forming means being recessed intermediate said restricting means and shouldered at said recess at a level just sufficiently above said restricting means to receive the distorted margin of a single unit to
25 be dispensed.

8. As a new article of manufacture a cup guide provided with cup obstructing means engageable with circumferentially spaced points of the margin of a cup traversing said
30 guide, said guide being recessed intermediate said points and shouldered to limit the number of cup margins receivable in the recessed portion of the guide upon distortion by said obstructing means.

35 9. As a new article of manufacture a cup dispenser comprising a guide having a cup positioning portion, circumferentially and axially spaced means positioned to obstruct the path of marginal portions of a cup below
40 said positioning portion and recessed wall portions intermediate said cup obstructing means limited as to their axial extent above the level of said means whereby to be adapted to receive the margin of a single cup distorted
45 in passing said means.

ERNEST HUFF.
